United States Patent Office

Des. 204,034
Patented Mar. 8, 1966

204,034

VTOL AIRCRAFT

Rolf Riccius and Bernhard Wolf, Bremen, Germany, assignors to Vereinigte Flugtechnische Werke Gesellschaft mit beschränkter Haftung früher "Weser" Flugzeugbau/Focke-Wulf/Heinkel-Flugzeugbau, Bremen-Flughafen, Germany

Filed Dec. 30, 1964, Ser. No. 83,229

Term of patent 14 years

(Cl. D71—1)

Fig. 1

Fig. 2

Fig. 3

Fig. 4

FIG. 1 is a perspective view of a VTOL aircraft embodying our new design;

FIG. 2 is a front elevational view thereof;

FIG. 3 is a top plan view thereof;

FIG. 4 is a side elevational view thereof.

The doors are shown in open position in FIGS. 2, 3 and 4.

We claim:

The ornamental design for a VTOL aircraft, substantially as shown.
